(57) CLAIM

I claim the ornamental design for a therapy pillow, as shown and described.

DESCRIPTION

FIG. 1 is perspective view of a therapy pillow.

FIG. 2 is a front elevation view of the therapy pillow.

FIG. 3 is a rear elevation view of the therapy pillow.

FIG. 4 is a left side elevation view of the therapy pillow.

FIG. 5 is a right side elevation view of the therapy pillow.

FIG. 6 is a top elevation view of the therapy pillow; and, FIG. 7 is a bottom elevation view of the therapy pillow. The broken lines in the drawings illustrate portions of the therapy pillow that form no part of the claimed design.
